Ariat, Inc., Miscellaneous Footwear Outsole Designs, disclosed prior to Jun. 27, 2005.

Primary Examiner—Celia A Murphy

(74) Attorney, Agent, or Firm—Cooley Godward Kronish LLP

(57) **CLAIM**

The ornamental design for a footwear outsole, as shown and described.

DESCRIPTION

FIG. 1 is a perspective view of a footwear outsole showing my new design;

FIG. 2 is a top plan view thereof;

FIG. 3 is a side view thereof; both sides being identical

FIG. 4 is a rear elevational view thereof;

FIG. 5 is a front elevational view thereof;

FIG. 6 is a perspective view thereof, shown applied to a footwear outsole; and,

FIG. 7 is a perspective view thereof, shown applied to a different footwear outsole.

The broken lines showing footwear in FIGS. 6 & 7 form no part of the claim.
